Primary Examiner — Angela J Lee(74) *Attorney, Agent, or Firm* — Socal IP Law Group LLP; Nikki M. Dossman; Steven C. Sereboff(57) **CLAIM**

The ornamental design for a lighting device with square bezel, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a top perspective view of a lighting device.

FIG. 2 is a bottom perspective view of the lighting device of FIG. 1.

FIG. 3 is a top view of the lighting device of FIG. 1.

FIG. 4 is a bottom view of the lighting device of FIG. 1.

FIG. 5 is a front view of the lighting device of FIG. 1.

FIG. 6 is a back view of the lighting device of FIG. 1.

FIG. 7 is a left-side view of the lighting device of FIG. 1; and,

FIG. 8 is a right-side view of the lighting device of FIG. 1. The broken lines shown represent unclaimed subject matter and form no part of the claimed design.
